OTTO PETERMANN, OF GROTON, NEW YORK, ASSIGNOR TO CORONA TYPEWRITER COMPANY, INCORPORATED, A CORPORATION OF NEW YORK.

TYPE-WRITING MACHINE.

1,116,476.

Specification of Letters Patent. Patented Nov. 10, 1914.

Application filed March 24, 1911. Serial No. 616,707.

To all whom it may concern:

Be it known that I, OTTO PETERMANN, a citizen of the Republic of Switzerland, and a resident of Groton, county of Tompkins, 5 and State of New York, have invented certain new and useful Improvements in Type-Writing Machines, of which the following is a full, clear, and exact description.

This invention relates more particularly 10 to the work sheet feed mechanism of typewriting machines.

The primary object of the invention is to provide simple and efficient feeding means 15 which will positively hold the work sheet about the platen to cause the sheet to move with the platen during its line or letter spacing movements, and to provide means whereby the work sheet may be readily and quickly released to permit the same to be adjusted 20 about the platen.

Other objects of the invention are to provide simple and efficient means for supporting feed rolls on opposite sides of the longitudinal center of the platen and to yieldingly hold said rolls against the platen; and to provide simple means whereby the feed rolls may be readily detached from the supporting means.

A further object of the invention is to 30 provide simple and efficient mechanism for supporting the feed rolls which may be readily made and assembled and which may be used in connection with various kinds of typewriting machines.

With these and other objects in view, the 35 invention will be hereinafter more particularly described with reference to the accompanying drawings, which form a part of this specification, and will then be pointed out in the claims at the end of the description.

In the drawings, Figure 1 is a plan view, partly in section and partly broken away, of one form of carriage embodying my invention. Fig. 2 is an enlarged transverse section, partly in elevation, taken on the line II—II of Fig. 1. Fig. 3 is an enlarged transverse section taken on the line III—III of Fig. 1, looking in the direction opposite 50 to that of Fig. 2; and Fig. 4 is a detail view of a tie element or member for the ball bearing of the carriage.

The invention is shown as applied to a typewriting machine in which the carriage

is adapted to be folded or shifted into compact relation to another part of the machine in order that the machine may be made more compact for transportation or for other purposes, though it will be understood that the invention may be applied to typewriting machines of various constructions.

The support 10 may be of a foldable or of a fixed character, and mounted on said support is a carriage bed 11 along which the carriage 12 is adapted to travel. A platen 13 is held to rotate in suitable bearings in the carriage frame and on either or both ends of the platen shaft is a knob 14 for rotating said platen, and at the front of the platen is a feed roll 15 and at the rear of the platen is a second and larger feed roll 16. The feed roll 15 has a shaft 17 extending parallel with the platen and the roll 16 a shaft 18 also extending parallel with the platen. Each feed roll has a plurality of 25 roll members 19 which are spaced apart by means of collars 20. The roll members may be of rubber or of any other material and are arranged to rotate independently on the feed roll shafts, and the spacing collars 20 are also mounted to move independently about the shafts. The shaft 18 at the rear of the platen is mounted in hook-shaped ends 21 of levers 22. These levers 22 are each pivoted at 23 to a bracket 24 which is 30 secured to the carriage base 25. There are a plurality of supporting means for each feed roll shaft and as many brackets 24 as there are supporting means. Each bracket 24 is substantially L-shaped in form and has 35 a foot 26 projecting from one side thereof and fastened by screws 27 or otherwise to the carriage base 25, the pivots 23 of the levers 22 being located on the horizontally arranged arms of said brackets. Each lever 22 has an arm 28 one end of which is attached to a spring 29, the other end of said spring being attached to an overhanging portion 29^a of the bracket, or to a screw 30 held in said portion 29^a or in any other desired way. 40 The threaded stem of the screw may pass within the spring 29 and by reason of the threads of the screw engaging the spring, the latter may have its tension varied as the said screw is adjusted. It will be seen that 45 the springs 29 serve to force the levers 22 on their pivots 23 toward the platen to cause the peripheral surface of the roll

105

members 19 to be brought into frictional engagement therewith and to an extent varying according to the tension of the springs 29.

5 A plurality of levers 31 are pivoted at 32 to the horizontally arranged arms of the brackets 24 on the side opposite to the levers 22, there being a lever 31 for each bracket, and each lever has an angular or 10 inclined arm 33, a horizontally extending part 35, and a vertical arm 36, the latter having an overhanging upper end to which is connected a spring 37. The spring 37 has one end attached to the arm 36 and its other 15 end held to the foot 26 or otherwise, as desired, and the tendency of said spring is to force the arm 36 downward to cause the roll 15 carried by the set of arms 33 to be moved with its roll into frictional engagement with 20 the surface of the platen 13 to hold the work sheet about the same. By providing the levers 22 and 31 with open hook-shaped portions to receive the rods or shafts 17 and 18, the said shafts will be held in the levers 25 against removal by the platen 13, but by removing the platen 13, the said shafts and feed rolls may be quickly removed or replaced at will. The platen may be removed by the removal of its rod or shaft or other- 30 wise, and to permit the arms to directly engage the shafts 17 and 18, the spacing collars 20, where the supporting levers are located, are cut-away for part of their circumference according to the extent to which 35 the hook-shaped parts engage the shafts.

To permit the feed rolls to hold the work sheet about the platen or to be readily and quickly released therefrom, various means may be employed. As shown a transversely- 40 extending rod 38 is provided, and this rod is mounted to rotate in the carriage ends and in the brackets 24. This rod is cut away on one side to form cam portions 39 and engaging said cam portions are arms or 45 projecting parts 40 forming a part of the levers 22. The arms 33 of the levers 31 extend in an opposite direction to that of the supporting arms of the levers 22, and said levers 31 at the lower edge thereof bear 50 upon the cam surfaces or cut-away portions 39 of the rod 38 so that by rotating the rod 38 in either direction the cam portion of the cut-away parts by engagement with the parts 35 of the levers 31 will release the 55 feed roll 15 from engagement with the platen, and by reason of the parts 40 of the levers 22 will release the feed roll 16 also from engagement with the platen to permit the sheet to be readily adjusted. The feed 60 roll 15 when released is forced against the tension of the springs 37 and the feed roll 16 against the tension of the springs 29 so that if the rod 38 is rotated one-fourth or one-half a revolution, the said rolls will be 65 held in disengaged position, while if the rod

is moved to the position shown in the drawings, the springs will quickly return the feed rolls into engagement with the platen. The rod 38 may be rotated by any suitable means as by a handle or by a finger portion 41 which may be held to either or both ends of said rod.

The carriage bed 11 is provided with a flange 42 along one edge thereof and a flange 43 along the other edge lengthwise thereof. This bed may have two depressed portions as 44 and 45 forming a channel or groove 46 lengthwise of the bed in which is adapted to roll a plurality of balls 47. Two balls are shown and these balls are 80 connected by a spacing or tie element 48, Fig. 4, the said spacing element being in the form of a strap and provided with apertures 49 in which are adapted to fit the balls 47. The upper surface of the balls 85 are adapted to move in a channel 50 in the carriage base 25 directly over the channel 46 of the carriage bed and in alignment therewith, and said channel may be formed by pressing or forming two ribs 51 and 52 90 as a part of the carriage base, the carriage base and bed being of sheet metal, as steel, to permit this construction.

A roll 53 supports the rear part of the carriage and this roll is rotatably held on a 95 stud 54 projecting inward from a flange 55 centrally of the carriage frame, and said roll is of a size relatively larger than the balls 47 and extends through a slot in the carriage base 25 so as to rest upon the upper 100 surface of the carriage bed 11. The flange 55 of the carriage frame moves under the in-turned end 56 of a bracket 57 which serves to hold the carriage from moving away from the bed 11. By means of the rolls 47 and its 105 tie element 48 an effective ball bearing for the carriage is provided, and the roll or disk 53 serves as an effective support and means by which the carriage may be readily moved lengthwise of its bed.

110 It will be understood that suitable propelling mechanism is employed for forcing the carriage along its bed in one direction, and it will also be understood that other features of a typewriting machine are employed, but as they form no part of this invention, they have not been illustrated or described as part of the application.

115 From the foregoing, it will be seen that simple and efficient means is provided for mounting feed rolls on opposite sides of the platen in such a way that the said feed rolls may be quickly released or caused to engage the platen; that simple means is provided whereby the feed rolls may be removed or 120 others placed in their stead; that simple means is provided for supporting and for operating the supporting means to release the feed rolls from engagement with the platen; and that the mechanism disclosed is 125 130

simple in construction and may be readily made and applied to various kinds of typewriting machines.

Having thus described my invention, I claim as new and desire to secure by Letters Patent:—

1. In a typewriting machine, the combination of a support, a carriage adapted to move along said support, a platen mounted in the carriage, a plurality of independent L-shaped brackets secured to the carriage, oppositely extending levers pivotally held to opposite sides of each bracket and having hooked ends, one of said levers of each bracket having a short engaging arm projecting outward therefrom, shafts detachably supported in the hooked ends of said levers, rolls rotatably held on said shafts, a spring for each lever tending normally to force the shafts supporting end toward the platen, and a rod having cam portions adapted to engage all of said levers and to simultaneously force the levers in a direction against the tension of the springs and in opposite directions to move the rolls away from the platen.

2. In a typewriting machine, the combination of a support, a carriage adapted to move along said support, a platen mounted in the carriage, a plurality of independent brackets secured to the carriage, oppositely extending levers pivotally held to each bracket on opposite sides thereof and having hooked ends, rods supported in the ends of said levers, rolls held on said rods, a spring for each lever tending normally to force the shaft supporting end toward the platen, said springs being vertically arranged and secured to the levers and to the bracket, and means adapted to engage all of said levers and to simultaneously force the levers in a direction against the tension of the springs and in opposite directions to move the rolls away from the platen.

3. In a typewriting machine, the combination of a support, a carriage having a base adapted to move along said support, a platen mounted in the carriage over the base, a plurality of independent substantially L-shaped brackets secured to the carriage base transversely thereof, oppositely extending levers pivotally held to each bracket on opposite sides thereof and having hooked ends, one of said levers of each bracket having a short engaging arm projecting outward therefrom, shafts detachably supported in the ends of said levers, spaced rolls rotatably held on said shafts, the rolls of one shaft being relatively larger than those of the other shaft, means tending normally to force the shaft supporting end of the levers toward the platen, and means adapted to engage all of said levers and to simultaneously force the levers to move the rolls away from the platen.

4. In a typewriting machine, the combination of a support, a carriage adapted to move along said support, a platen mounted in the carriage, a plurality of independent brackets secured to the carriage, transversely thereof and extending under and to the rear of the platen, oppositely extending levers pivotally held to each bracket on opposite sides thereof, shafts supported in the ends of said levers, spaced rolls held on said shafts, means tending normally to force the rolls toward the platen, and means for forcing the rolls away from the platen.

5. In a typewriting machine, the combination of a support, a carriage adapted to move along said support, a platen mounted in the carriage, a plurality of independent and substantially L-shaped brackets secured to the carriage, transversely thereof and having a part extending vertically at the rear thereof, oppositely extending levers pivotally held to each bracket on opposite sides thereof and having hooked ends, shafts detachably supported in the ends of said levers, spaced rolls rotatably held on said shafts, a spring for each lever located at the rear of the platen and secured at one end to the lever and at its other end to the bracket to which the lever is pivoted and tending normally to force the rolls toward the platen, and means adapted to engage all of said levers and to simultaneously force the levers in a direction against the tension of the springs and in opposite directions to move the rolls away from the platen.

6. In a typewriting machine, the combination of a support, a platen, a plurality of L-shaped brackets secured to the support, two oppositely extending levers pivotally held to each bracket and having hooked ends, shafts supported in the ends of said levers, roll members movable independent of said shafts, means for yieldingly forcing the levers in one direction, and a rod having cam portions for simultaneously forcing the levers in opposite directions to disengage the rolls from the platen.

7. In a typewriting machine, the combination of a carriage, a platen, a plurality of L-shaped brackets secured to the carriage, two oppositely extending levers pivotally held to each bracket and having hooked ends, feed rolls supported in the ends of said levers on opposite sides of the platen and arranged parallel therewith, springs for yieldingly forcing the levers in one direction, and a rotary rod having cam portions for simultaneously forcing the levers in opposite directions against the tension of the springs.

8. In a typewriting machine, the combination of a carriage having a base, a platen mounted in the carriage over the base, a plurality of independent L-shaped brackets held to the base, a set of levers pivotally

held to each bracket and extending on opposite sides of the center of the platen, springs held to the brackets and to the levers and tending normally to force the levers in one direction, feed rolls mounted in said levers on opposite sides of the platen and in parallel relation thereto, and means for disengaging the feed rolls from the platen.

9. In a typewriting machine, a carriage having a base, a platen mounted in said carriage over the base, a plurality of independent brackets secured to the carriage base, a set of levers pivotally mounted on

each bracket, feed rolls detachably mounted in the levers, independent springs held to the brackets and to the levers and normally and independently forcing the levers in one direction, and a rod mounted in the support and having means to move the levers against the tension of the springs.

This specification signed and witnessed this 20th day of March A. D. 1911.

OTTO PETERMANN.
